UNITED STATES PATENT OFFICE.

PARKER DODGE, OF WASHINGTON, DISTRICT OF COLUMBIA.

SOUND-BOX.

1,251,355.

Specification of Letters Patent. Patented Dec. 25, 1917.

Application filed May 18, 1915. Serial No. 28,911.

To all whom it may concern:

Be it known that I, PARKER DODGE, a citizen of the United States, residing at Washington, in the District of Columbia, have 5 invented certain new and useful Improvements in Sound-Boxes, of which the following is a specification.

This invention relates to sound boxes for gramophones, graphophones and the like and 10 the principal features of novelty reside in the mounting of the diaphragm.

The invention has a special utility and 15 function when combined with the characteristic features of the sound box described and 20 claimed in my copending application Serial Number 12,578, filed March 6, 1915. Accordingly, in order to disclose the best embodiment known to me, and to permit the making of specific claims to that combination, 25 I hereinafter describe the invention as applied to the structure of my said application. I do not, however, limit myself thereto, as certain advantages of the invention may be secured with other sound boxes in 30 which the diaphragm is rigidly mounted.

The invention consists in a sound box in 35 which the diaphragm is rigidly mounted and held under a uniformly distributed radial compressive stress acting in the plane of the 40 diaphragm. A diaphragm so mounted is peculiarly inert and devoid of inherent resonance; it vibrates freely with a relatively wide amplitude, giving an increased volume and roundness of tone, and an increased response to sibilants and "breathy" sounds.

I shall now describe the invention as applied to a gramophonic reproducer, in which it has been successfully used. Those skilled in the art will appreciate its applicability to 45 other types of reproducer and to recorders by the making of simple substitutions well known in the art.

Referring to the drawings:

Figure 1 is a front elevation of a sound 50 box having my invention applied;

Fig. 2 is an axial section thereof;

Fig. 3 is an enlarged fragmentary view similar to Fig. 2;

Fig. 4 is a perspective view of a diaphragm 55 clamping ring of preferred form, a part of the ring being shown broken away to clearly show the form; and

Fig. 5 is an elevation of a diaphragm with the stresses to which it is subjected diagrammatically indicated.

In the drawings 6 represents the usual

rubber connector sleeve for connecting the sound box or reproducer to the goose neck or tone arm of the machine on which it is to be used. The sleeve has the usual brass 60 lining tube 7 which fits over the end of the goose neck, and is provided with the usual bayonet lock pin (not shown). The cup-shaped body 9 of the sound-box, which is of metal, is held to the connector sleeve 6 by 65 means of screws 10 and by means of a metal weight ring 11 which closely embraces the sleeve 6 and is sealed to the rear face of the box-body 9 with a thin layer of bees-wax or similar plastic adhesive 12. The purpose of 70 this weight is to damp any vibrations which might be set up in the box-body 9.

The box-body 9 is internally threaded as indicated at 13 and is provided with an aperture 14 leading through connector sleeve 6 75 to the goose neck or tone arm.

The diaphragm 15 which preferably is of mica is clamped between two rings 16 and 17 of substantially identical form, each having a central aperture which I prefer to make 80 of substantially the size of aperture 14. The face of each of the rings 16 and 17 toward the diaphragm is a surface of revolution. The generating curve is tangent or approximately tangent to the contacting face of the 85 diaphragm at or near its periphery and curves gradually away from such face toward the center of the diaphragm. The clearance between the opposed faces of the rings 16 and 17 need be only slightly greater than the maximum amplitude of vibration 90 of the diaphragm and is somewhat exaggerated in the drawing. The rings 16 and 17 may be of any relatively rigid material. The best results have been secured with 95 celluloid, but successful use has been made of metals, for example aluminum and brass. The brilliancy of tone seems to increase with the hardness of the material used for the rings.

The rear ring 16 is sealed to the rear wall of the box-body 9 by a thin layer 18 of bees-wax or similar adhesive plastic and the front ring 17 is pressed toward it by a nut ring 19. Paper gaskets 20 may be interposed between 100 front ring 17 and nut ring 19, partly to equalize the pressure by their resiliency and partly to permit nut ring 19 to turn more freely on ring 17 in assembling the sound-box.

The vibrator or stylus arm 21 is mounted 105 on cone pivot screws 22 which are threaded

in lugs 23 and locked with check nuts 24. It has the usual needle socket in which needles may be clamped by the set screw 25. The stylus arm 21 is connected to the center 5 of the diaphragm 15 by means of a threaded stud 26 and nut 27, the usual washers 28 being used to distribute the pressure.

The structure so far described forms the subject matter of my application above 10 identified and consequently is not broadly claimed herein.

To apply my invention to such a sound box, it is necessary simply to clamp the diaphragm 15 between the rings 16 and 17 in 15 such a way that it will be held by them under a radially acting compressive stress. Any preferred method of securing this result may be adopted. One convenient method is loosely to assemble the diaphragm 15, clamping rings 16 and 17, washers 20 and nut ring 20 19 in the box-body 9, then to deflect the diaphragm an amount approximating the maximum deflection of the diaphragm desired in reproducing from records, and finally while 25 holding the diaphragm so deflected to set up the nut ring 19 until the periphery of the diaphragm is clamped fast between the rings 16 and 17. This holds the periphery in the contracted state resulting from the deflection 30 of the diaphragm. This method forms a part of the subject matter of my copending application, Serial Number 28,910, filed May 18, 1915, and hence is not claimed herein.

In Fig. 5 I illustrate diagrammatically 35 the diaphragm and the stresses to which it is subjected. The arrows are intended to illustrate by their close spacing a uniformly distributed stress acting radially at all points around the periphery or line of clamping of 40 the diaphragm.

The imparting of this compressive stress to a rigidly mounted diaphragm seems invariably to increase the roundness and loudness of the tone produced by such diaphragm, and renders certain sounds such 45 as sibilants clearly audible. The increased sensitiveness of the diaphragm, when so stressed, increases the tendency to whine and blast under some conditions, but I have 50 found that the use of the conoidally recessed rings of my prior application completely neutralizes this effect. Furthermore the stressed diaphragm when applied to the sound box of my prior application markedly 55 increases the range of records which may be reproduced therewith.

Thus the invention resides first in the stressed diaphragm, and second in the combination of this with clamping means having conoidally recessed proximate clamping faces. Different methods and means for securing the stressing and different mechanical expressions of the clamping members, etc., are possible, are contemplated and fall with- 60 in the scope of the invention. The clamping 65

members may be made of materials of different degrees of resiliency, provided they are substantially rigid.

Having thus described the invention what I claim is:—

1. In a sound box, the combination of a 70 box body; a vibrator mechanism; a substantially rigid support for the peripheral portion of a diaphragm, carried by said box body; and a flexible diaphragm held by said support in a state of radial compression, and operatively connected with said vibrator mechanism.

2. In a sound box, the combination of a 80 box body; a vibrator mechanism; a substantially rigid support engaging the peripheral portion of a diaphragm and carried by said box body; and a mica diaphragm held by said support in a state of radial compression, and operatively connected with said vi- 85 brator mechanism.

3. In a sound box, the combination of a 90 box body; a vibrator mechanism; relatively rigid clamping means mounted in said box body for exerting a clamping action upon the faces of a diaphragm at or near its periphery; and a flexible diaphragm held by said clamping means in a state of radial compression, and operatively connected with 95 said vibrator mechanism.

4. In a sound box, the combination of a 100 box body; a vibrator mechanism; celluloid clamping means mounted in said box body for exerting a clamping action upon the faces of a diaphragm at or near its periphery; and a flexible diaphragm held by said clamping means in a state of radial compression, and operatively connected with 105 said vibrator mechanism.

5. In a sound box, the combination of a 110 box body; a vibrator mechanism; clamping means of relatively rigid material mounted in said box-body and formed with opposed conoidally recessed clamping faces for receiving an interposed diaphragm, said faces 115 being so formed as each to have an annular area of contact with the proximate face of such diaphragm at or near the periphery thereof, and to curve gradually away from said diaphragm toward the center; and a 120 diaphragm held by said clamping means in a state of radial compression, and operatively connected with said vibrator mechanism.

6. In a sound box, the combination of a 125 box body; a vibrator mechanism; clamping means of relatively rigid but elastic material mounted in said box body and formed with opposed conoidally recessed clamping faces for receiving an interposed dia- 130 phragm, said faces being so formed as each to have an annular area of contact with the proximate face of such diaphragm at or near the periphery thereof, and to curve gradually away from said diaphragm to-

ward the center; and a diaphragm held by said clamping means in a state of radial compression, and operatively connected with said vibrator mechanism.

5. 7. In a sound box, the combination of a box body; a vibrator mechanism; clamping means of celluloid mounted in said box body and formed with opposed conoidally recessed clamping faces for receiving an interposed diaphragm, said faces being so formed as each to have an annular area of contact with the proximate face of such diaphragm at or near the periphery thereof, and to curve gradually away from said diaphragm toward the center; and a diaphragm held by said clamping means in a state of radial compression, and operatively connected with said vibrator mechanism.

10. 8. In a sound box the combination of a relatively rigid diaphragm mount having an annular diaphragm supporting area merging into a central recess which flares gradually away from the face of the supported

diaphragm toward the center; means for clamping the periphery of a diaphragm 25 against said mount; a flexible diaphragm held by said clamping means in a state of radial compression; and a suitable vibrator mechanism for said diaphragm.

9. In a sound box the combination of a 30 relatively rigid diaphragm mount having an annular diaphragm supporting area merging into a central recess which flares gradually away from the face of the supported diaphragm toward the center; a second diaphragm mount having a surface configuration similar to that of the first diaphragm mount; means for forcing said mounts together; a flexible diaphragm held between said mounts in a state of radial compression; and a suitable vibrator mechanism for 35 said diaphragm.

In testimony whereof I have signed my name to this specification.

PARKER DODGE.
